SWITCH FOR GENERATORS

Elliott H. Otterbacher, Chicago, Ill., assignor to
 Associated Electric Laboratories, Inc., Chicago,
 Ill., a corporation of Delaware

Application January 11, 1939, Serial No. 250,330

2 Claims. (Cl. 200—153)

The present invention relates to alternating current generators of the hand operated magneto type, such, for example, as generators of the character utilized in ringing or signaling over telephone lines, and, more particularly, to improvements in 5 rotor drive and switch operating mechanisms of the type embodied in generators of this character.

It is an object of the present invention to provide, in a generator of the character described, an improved rotor drive and switch operating mechanism which is of extremely simple, rugged, compact and economical construction.

It is a further object of the invention to provide, in a generator of the character described, an improved rotor drive and switch operating mechanism which possesses the above structural characteristics and which operates without lost motion or frictional drag to provide a positive 10 driving connection between the drive shaft and the rotor of the generator and to actuate an associated circuit controlling device.

In general, the objects as set forth above are realized in accordance with the present invention by providing a magneto generator which includes a rotor, a drive shaft mounted for rotary and axial movement and a driving connection between the shaft and the rotor, together with a circuit controlling element operative in response 15 to axial movement of the shaft. The driving connection includes a pair of cooperating elements, one of which is provided with a slot having a side terminating in a tapered camming surface. The other element includes a projection 20 extending within the slot and having a side extending parallel with but normally displaced from the side of the slot and terminating in a tapered camming surface normally engaging the camming surface provided by the slot. More 25 particularly, the element in which the slot is formed comprises a rotatable sleeve in which the drive shaft is journaled and carrying a gear embodied in the driving connection through which power is transmitted from the drive shaft to the 30 rotor element. The element from which the above-mentioned projection extends is mounted upon the drive shaft. By virtue of this arrangement, the camming surfaces cooperate to impart axial movement to the shaft in response to 35 rotation of the shaft, and the parallel sides of the projection and the slot engage positively to arrest the axial movement of the shaft after a predetermined rotary movement thereof.

The novel features believed to be characteristic of the invention are set forth with partic-

ularity in the appended claims. The invention both as to its organization and method of operation, together with further objects and advantages thereof, will best be understood by reference to the specification taken in connection with the accompanying drawings in which Figure 1 is an elevated perspective view of a generator having embodied therein the features of the invention as briefly outlined above; Fig. 2 is a front view in elevation of the generator 10 shown in Fig. 1; Fig. 3 is an exploded view illustrating the elements of the field structure embodied in the generator shown in Fig. 1; Fig. 4 is a diagrammatic view in elevation illustrating certain of the elements embodied in the generator shown in Fig. 1; and Fig. 5 is an exploded view illustrating certain elements of the driving mechanism embodied in the generator shown in Fig. 1.

Referring now to the drawings, the generator 20 there illustrated comprises a supporting structure 10 which includes a back or mounting panel 11, a base panel 12, and a pair of spaced-apart parallel extending side panels 13 and 14. This supporting structure is constructed of non-magnetic material, such, for example, as brass or insulating material, and preferably is formed by casting. The back panel 11 of the supporting structure 10 is provided with countersunk drill holes 15 which are adapted to accommodate 30 mounting screws or bolts, not shown. The side panels 13 and 14 are respectively provided with openings 13a and 14a having positioned therein the windings 16 and 17 of a field structure 18 which is secured to the base 12 of the supporting 35 structure by means of screws 9. For the purpose of varying the reluctance of the magnetic circuit provided by the field structure 18 there are provided two rotor elements 19 and 20 which are mounted upon the heads 21a and 21b, respectively, of a mandrel 21 carried by a shaft 22. The rotor element 19 is secured to the mandrel head 21a by means of four rivets 23 disposed around the mandrel head 21a and extending through this head and the rotor element 19. The 40 other rotor element 20 is similarly mounted upon the mandrel head 21b. The shaft 22, upon which the mandrel 21 is rigidly mounted by means of a set screw 24, is journaled in bearing members respectively mounted in the side panels 13 and 14. This shaft carries at its right extremity a small gear 25 through which power is adapted to be transmitted to the shaft 22.

More particularly, the driving mechanism for the rotor elements 19 and 20 includes a shaft 26 55

rotatably supported within a bearing member 27 which is mounted in any suitable manner in an opening provided in the side panel 14. The shaft 26 has rigidly secured to its right extremity a 5 collar 28 upon which is mounted a crank lever 29. Rotary movement of the shaft 26 occasioned by operation of the crank 29 is transmitted to the shaft 22 through a driving connection including a pair of clutch elements 30 and 31 and a gear 10 train comprising the gear 25 and three additional gears 32, 33 and 34. More particularly, the clutch element 31 is in the form of a sleeve journaled in the bearing member 27 and having its internal surface arranged to journal the shaft 26. The 15 sleeve 31 has rigidly mounted on the right end thereof the gear 34 which meshes with the gear 33. The two gears 33 and 32 are rigidly secured together and are journaled upon a stub shaft 35 extending from and mounted upon the side panel 20 14. The two gears 32 and 33 are restrained against longitudinal movement by means of a collar 36 secured to the shaft 35 by a set screw 37. Similarly, the sleeve 31 is restrained against 25 axial movement to the right by means of a collar 38 secured to the sleeve 31 by a set screw 39 and having a smooth surface frictionally engaging the adjacent surface of the bearing member 27.

The shaft 26, upon which the crank 29 is mounted, is axially movable within the sleeve 31 30 to actuate between two operating positions the movable spring 40 of a spring pile 41 including two additional springs 42 and 43. The actuating element for the movable spring 40 comprises a disk 44 formed of fibre or other insulating material and carried by a collar 45 which is secured to the shaft 26 by means of a set screw 46. As best shown in Fig. 5 of the drawings, in order to move the shaft 26 axially to the left from the position shown in Fig. 1 of the drawings, against 40 the spring bias normally exerted thereon by the movable contact spring 40, the sleeve 31 is provided with two oppositely disposed slots, one of which is indicated at 47, each terminating in a V-shaped notch the tapered sides of which provide camming surfaces. These slots each include 45 extended parallel straight sides formed by milling the sleeve 31, the V-shaped notches being thereafter formed by cutting beyond the bases of the milled sides of the sleeve. Thus, the slot 47 defines two straight side walls 47_a and 47_b in the sleeve 31. The clutching element or collar 30 is rigidly secured to the shaft 26 by means 50 of a set screw 39_a and is provided with a pair of oppositely disposed projections arranged respectively to extend within the slots formed in opposite sides of the sleeve 31 in the manner described above. Thus, the collar 30 has formed integral therewith a projection 48 having straight 55 parallel side walls adapted respectively to engage the straight side walls 47_a and 47_b of the slot 47, but normally displaced therefrom, and a V-shaped end, the tapered sides of which normally snugly engage the V-shaped end of the slot 47. Thus, the tapered sides of the projection 48 constitute 60 camming surfaces normally engaging the camming surfaces of the slotted portion 47 of the sleeve 31. The other projection extending from the collar 30 is constructed and arranged in a similar manner to extend within the other slot formed in the end of the sleeve 31 and oppositely disposed with respect to the slot 47.

The springs of the spring pile 41 are mounted upon the side panel 13 through the provision of a mounting assembly which comprises four insulating members 49, a pair of mounting screws

50 and a face plate 51. More particularly, the screws 50 extend through registering openings drilled through the face plate 51, the insulating members 49 and the contact springs of the spring pile 41, and are threaded into tapped drill holes 5 formed in the side panel 13. In this manner the contact springs 40, 42 and 43 are insulated from each other and from the supporting structure 10.

The field structure 18 is of the improved construction and arrangement disclosed and claimed in copending application Serial No. 250,329, Albert E. Woodruff, filed January 11, 1939. As best shown in Fig. 3, this field structure comprises a substantially U-shaped field member 52, having two legs 52_a and 52_b, upon which the windings 16 and 17 are respectively mounted, and a base portion 52_c. The base portion 52_c is recessed to receive a permanent magnet 53 and is provided with drill holes 54 for receiving the mounting screws 9, and with additional holes 55_a and 55_b for receiving the field structure assembly screws 56_a and 56_b. The upper ends of the legs 52_a and 52_b are notched at 57_a and 57_b, respectively, so that each leg is provided with two separated pole faces. The pole face portions of the legs 52_a and 52_b are arranged to be oppositely disposed with respect to the pole face portions 58_a and 58_b of a plate or field member 59 which in cooperation with the assembly screws 56_a and 56_b serves rigidly to mount the permanent magnet 53 upon the base portion 52_c of the field member 52. More particularly, the permanent magnet bar 53 is provided with oppositely disposed slots 53_a and 53_b within which the assembly screws 56_a and 56_b are respectively disposed when the field structure 35 is assembled, and the field member 59 is provided with tapped drill holes 60_a and 60_b into which the assembly screws or bolts 56_a and 56_b, respectively, are threaded. Although the magnet bar 53 may be formed of any desired magnetic material, it is preferably formed of an alloy consisting of 5 to 40 percent nickel, 7 to 20 percent aluminum, 0.5 to 30 percent cobalt and the remainder iron, such, for example, as the alloy commercially known as "Alnico."

As indicated above, the rotor elements 19 and 20 are arranged to vary the reluctance of the magnetic circuit formed by the field structure 18 thereby to cause induced voltages to be developed in the windings 16 and 17. More particularly, 50 each rotor element is provided around its periphery with alternate magnetic and nonmagnetic sections which are adapted to be moved between the oppositely disposed pole faces of the field structure. Thus, the rotor element 19 is 55 provided with a plurality of teeth or magnetic sections 19_a which are alternated with a plurality of cut-out or nonmagnetic portions 19_b. The teeth 19_a of the rotor element 19 are, when the generator is assembled, adapted to be moved 60 between the pole face portions 58_a of the field member 59 and the oppositely disposed pole faces of the leg 52_a of the field member 52. In a similar manner the rotor element 20 is provided with teeth or magnetic sections 20_a which are alternated with cut-out portions or nonmagnetic sections 20_b. The teeth of the rotor element 20 are 65 adapted to be moved between the pole face portions 58_b of the field member 59 and the oppositely disposed pole faces of the leg 52_b of the field member 52. The arrangement is such that the teeth or magnetic portions of one of the rotor elements register with the cut-out or nonmagnetic sections of the other rotor element, it being 70 observed that each rotor element is provided with 75

the same number of teeth, and further, that the number of teeth of the elements partially determines the frequency output of the generator. More particularly, and as best shown in Fig. 4, the 5 rotor element 19 is mounted upon the mandrel head 21a in a manner such that the teeth 19a thereof register with the cut-out or nonmagnetic portion 20b of the rotor element 20, and, correspondingly, the cut-out portions 19b register with 10 the teeth 20a of the rotor element 20. It will be observed that the rotor elements are mounted upon the mandrel heads in such a manner that, with the shaft 22 occupying a position such that two of the teeth 20a of the rotor element 20 are 15 positioned exactly between the two pole faces 58a and the oppositely disposed pole faces of the leg 52b, one of the teeth 19a of the rotor element 19 registers with the slot 57a of the leg 52a and none of the teeth of this element are positioned 20 opposite the pole faces 58a and the oppositely disposed pole faces of the leg 52a. By virtue of this arrangement and during rotation of the rotor elements the predominant portion of the flux developed by the permanent magnet bar 53 is 25 alternately directed through the legs 52b and 52a of the field member 52. Thus, the flux linking the windings 16 and 17 is varied in response to rotation of the rotor elements 19 and 20 so that undulating voltages are developed in the coils 30 16 and 17.

In assembling the elements of the generator as described above, the field structure, as shown in Fig. 3, is first assembled in the manner just explained, with the windings thereof positioned 35 upon the legs 52a and 52b, following which the assembled field structure is positioned between the side panels 13 and 14 of the supporting structure 10 and is loosely secured to the base member 12 by means of the screws 9. The mandrel 21 40 with the rotor elements 19 and 20 mounted thereon is next positioned between the side panels 13 and 14 with the teeth of the rotor elements extending between the pole faces of the field structure 18, it being pointed out that the length of 45 the shaft portion of the mandrel 21 is substantially the same as the distance between the inner surfaces of the side panels 13 and 14 so that no appreciable axial movement of the rotor elements is permitted. Following this operation the 50 shaft 22 with the gear 25 mounted thereon is inserted through the bearing carried by the side panel 14, through the mandrel 21, and into the bearing carried by the side panel 13. The mandrel 21 is then secured to the shaft 22 by tightening 55 the set screw 24. The next operation is that of positioning the pole faces of the field structure so that the teeth of the rotor elements 19 and 20 are accurately centered between the slots defined by the respective oppositely disposed 60 pole faces. To this end a suitable thickness gauge is inserted between the teeth 19a of the rotor element 19 and the adjacent pole faces 58a of the field member 59, and a second thickness gauge of equal thickness is inserted between the teeth 20a 65 of the rotor element 20 and the pole faces 58b of the field member 59. Thus, by a proper selection of the thickness gauges used the teeth of the rotor elements 19 and 20 may be accurately centered with respect to the associated pole faces 70 of the field structure. Following this centering operation the screws 9 are tightened rigidly to secure the field structure 18 to the base 12 of the supporting structure 10. The next assembly operation is that of mounting the spring pile 41 75 and its assembly upon the side panel 13, which

operation will be obvious in view of the foregoing explanation. The driving mechanism of the generator is assembled by properly positioning the sleeve 31 longitudinally with respect to the bearing 27 with the gear 34 rigidly mounted thereon 5 and the collar 38 loosely positioned thereon and thereafter tightening the set screw 39. Following this assembly operation the shaft 26, with the crank 29 mounted thereon, is inserted through the sleeve 31, the collar 30 and the collar 10 45 carrying the disk 44. The two collars 30 and 45 are now properly positioned axially along the shaft 26, following which the set screws 30a and 46 are tightened rigidly to secure these elements to the shaft 26. The final assembly operation 15 is that of securing the gears 33 and 32 upon the stub shaft 35 in mesh with the gears 25 and 34, respectively. To this end the gear combination comprising the two gears 32 and 33 is telescoped over the shaft 35 and the collar 36 is mounted 20 on the shaft 35 in abutting relation with the gear 32. Finally, the set screw 37 is tightened to secure the collar 36 to the shaft 35 and thus prevent axial movement of the gears 32 and 33.

In the operation of the device, and when the 25 crank 29 is turned in a clockwise direction from the position shown in Fig. 1 of the drawings, power is transmitted through the elements 30 and 31 and the gear train comprising the gears 34, 33, 32 and 25 to the shaft 22 upon which 30 the rotor elements 19 and 20 are mounted thereby to cause rotary movement of these elements. During the preliminary movement of the shaft 26 the inertia of the rotor assembly and the gear train together with the mechanical resistance 35 of the gears and bearings more than offsets the bias exerted upon the end of the shaft 26 by the movable contact spring 40. Accordingly, the engaged camming surfaces defined by the V-shaped notches formed in the sleeve 31 and the 40 tapered ends of the camming projections carried by the collar 30, cooperate to cause the shaft 26 and the disk 44 carried thereby to be deflected to the left. During this longitudinal movement of the shaft 26 the movable contact spring 40 45 is moved out of engagement with the spring 43 and into engagement with the spring 42. The longitudinal movement of the shaft 26 is limited through engagement of the straight sides of the camming projection 48 with the adjacent straight 50 walls of the slots formed in the sleeve 31. Thus, after a small longitudinal movement of the shaft 26, the upper straight side of the camming projection 48 is moved into engagement with the adjacent slot side 47a to establish a driving connection between the shaft 26 and the sleeve 31. Substantially simultaneously the straight side of 55 the other camming projection engages the adjacent side of the other slot formed in the sleeve 31. Thus, it will be seen that the longitudinal 60 or axial movement of the shaft 26 is limited and is positively arrested without frictional engagement between any of the moving parts of the driving mechanism and the supporting structure. After the direct drive connection between the 65 shaft 26 and the sleeve 31 is established, continued rotation of the shaft 26 is transmitted through the above described speed increasing gear train to the shaft 22, thus causing the teeth of the rotor elements 19 and 20 to be moved 70 relative to the pole faces of the field structure 18. During this continued rotation of the rotor elements 19 and 20 and each time two of the teeth of the element 20 are moved into registration with the pole faces 58b of the field member 75

59, an obvious low reluctance path including the leg 52_b of the field member 52 is established. At this instant and as explained above, the teeth of the rotor element 19 are out of registration 5 with the pole faces 58_a of the field member 59 and the oppositely disposed pole faces of the leg 52_a. Hence the reluctance of the magnetic circuit, including the leg 52_a and the permanent magnet bar 53, is relatively high as compared 10 to the reluctance of the flux path including the leg 52_b. Accordingly, a predominant portion of the flux developed by the permanent magnet bar 53 is directed through the leg 52_b of the field member 52. It will, of course, be appreciated 15 that the flux traversing the leg 52_b of the field member 52 gradually increases each time two teeth of the rotor element 20 are moved into registration with the pole faces 58_b of the field member 59 and is gradually decreased as the two teeth are moved out of registration with these pole faces. In a similar manner, each time any pair of teeth of the rotor element 19 are moved 20 into registration with the pole faces 58_a of the field member 59 the reluctance of the magnetic circuit including the leg 52_a is gradually decreased so that the flux traversing this leg of the field structure is gradually increased, whereas, when the two teeth are moved out of registration with the indicated pole faces 58_a the flux 25 traversing the leg 52_a is caused to decrease. Since the teeth of the rotor element 19 register with the slots of the rotor element 20 it will be apparent that an increase in the flux traversing the leg 52_b of the field structure is accompanied by a decrease in the flux traversing the leg 52_a and, conversely, an increase in the flux traversing the leg 52_a of the field structure is accompanied by a decrease in the flux traversing the leg 52_b. Due to the change in the flux linking the respective 30 windings 16 and 17 undulating or alternating voltages are developed in these windings. By connecting the windings in series aiding relation the sum of the voltages developed by the two windings may be impressed upon the output terminals, not shown, of the generator. This type 35 of connection is employed when a high voltage, low current output is desired. Alternatively, the windings 16 and 17 may be connected in parallel relationship to supply a low voltage, high current demand.

40 When rotation of the shaft 26 is arrested and the crank 29 is released, the bias exerted by the movable spring 40 upon the disk 44 causes the shaft 26 to be returned to its axial normal position wherein the tapered ends of the projections 45 of the collar 38 nest in the V-shaped ends of the slots provided in the sleeve 31. During such axial movement of the shaft 26 the movable spring 40 is moved out of engagement with its associated contact spring 42 and back into engagement with its associated contact spring 43. The contact springs 40, 42 and 43 may be utilized for any desired control purposes, although, 50 in the application mentioned above, it is con-

templated that these springs shall be used for the purpose of connecting and disconnecting the generator to and from the conductors of an associated telephone line and for the additional purpose of operatively associating the substation apparatus of an associated substation with the telephone line when the generator is disconnected from the line.

5 While there has been described what is at present considered to be the preferred embodiment of the invention, it will be understood that various modifications may be made therein, and it is intended in the appended claims to cover all such modifications as fall within the true spirit and scope of the invention.

15 What is claimed is:

1. In a magneto generator including a rotor, a drive shaft mounted for rotary and axial movement and a driving connection between said shaft and said rotor, a circuit controlling element operative in response to axial movement of said shaft, a pair of cooperating elements included in said driving connection, one of said elements being provided with a slot having parallel sides terminating in a substantially V-shaped camming surface, the other of said elements comprising a collar provided with a projection extending within said slot, said projection having sides extending parallel with but normally displaced from the parallel sides of said slot and terminating in a substantially V-shaped end to provide a camming surface which normally engages the camming surface of said slot, means including said camming surfaces for imparting axial movement to said shaft in response to rotation of said shaft, and means including said parallel sides of said slot and said projection for positively arresting axial movement of said shaft after a predetermined rotary movement of said shaft.

2. In a magneto generator including a rotor, a drive shaft mounted for rotary and axial movement and a driving connection, including a gear train, between said shaft and said rotor, a rotatable sleeve in which said shaft is journaled and having mounted thereon one of the gears of said gear train, said sleeve being provided with a slot having parallel sides terminating in a substantially V-shaped camming surface, a collar mounted upon said shaft and provided with a projection extending within said slot, said projection having sides extending parallel with but normally displaced from the parallel sides of said slot and terminating in a substantially V-shaped end to provide a camming surface which normally engages the camming surface of said slot, means including said camming surfaces for imparting axial movement to said shaft in response to rotation of said shaft, and means including said parallel sides of said slot and said projection for positively arresting the axial movement of said shaft after a predetermined rotary movement of said shaft.
